UNITED STATES PATENT OFFICE.

JAMES F. THAYER, OF PROVIDENCE, RHODE ISLAND.

COMBINED STAPLE AND DIE.

SPECIFICATION forming part of Letters Patent No. 293,540, dated February 12, 1884.

Application filed November 21, 1883. (No model.)

To all whom it may concern:

Be it known that I, JAMES F. THAYER, a citizen of the United States, residing at Providence, in the county of Providence and State 5 of Rhode Island, have invented certain new and useful Improvements in Combined Staples and Dies; and I do hereby declare the following to be a full, clear, and exact description of the invention, such as will enable others skilled in the art to which it appertains to 10 make and use the same, reference being had to the accompanying drawings, and to letters or figures of reference marked thereon, which form a part of this specification.

15 My present invention relates to staple-fasteners; and it consists, essentially, of a staple having an enlarged base or head provided with clinching or prong deflecting dies wrought therein, and further provided with two or 20 more penetrating - prongs, the whole being formed from a single metallic blank or piece of metal, and constituting a new article of manufacture.

25 My invention further consists in combining two of said staples to produce a fastening for attaching together papers, fabrics, or other analogous material or articles, whereby the prongs of one of the staples are inserted through the material from the upper side thereof, and 30 the other staple being inserted from the under or opposite side of the material, but at right angles with the former staple. The prongs of both staples are now pressed toward each other by suitable means, when the points thereof, 35 coming each in contact with the deflecting-dies wrought in the base of its fellow staple, are forcibly clinched thereunder, thereby producing a very attractive, simple, and inexpensive fastener, all as will be more fully herein- 40 after set forth.

In the accompanying sheet of drawings, Figure 1 represents (enlarged) a vertical central section through my improved staple when used as a fastening. Fig. 2 represents a side 45 view of the staple. Fig. 3 represents an inverted plan view of the blank from which the

staple is formed. Fig. 4 represents a central section through the staple on line $\alpha\alpha$ of Fig. 3, showing the prong-deflecting dies therein.

A represents, in the drawings, my improved 50 "staple," so-called, having a head or table, A', into which is formed or wrought the dies or deflectors a , the latter being enlarged or widened at the outer edge of the table. Said staple is further provided with the prongs a' . 55 At a' (see Fig. 3,) adjacent to the prongs, the head is cut away slightly, whereby the edge of said head A', &c., is adapted to project beyond the prongs. (See Figs. 1, 2.)

I am well aware that staples having two or 60 more prongs and having heads of various formations are old. Therefore I do not make claim to such staples; but

What I do claim, and desire to secure by Letters Patent, is—

1. As an improved article of manufacture, 65 the pronged and enlarged headed staple herein described, provided with clinching or deflecting dies wrought or formed in said head and integral therewith, substantially as and for 70 the purpose set forth.

2. The staple A, herein described, consisting of the enlarged head A' and prongs a' , 75 said head having concave deflecting surfaces or dies formed on its under side at right angles to the prongs, substantially as shown and set forth.

3. The method of fastening, consisting in inserting the prongs of the die-headed staple, 80 herein described, through the fabric or material at right angles to a similar staple inserted through the material from the opposite side thereof, the ends of the prongs being then clinched beneath the heads and against the dies of the staples, all substantially as shown 85 and set forth.

In testimony whereof I have affixed my signature in presence of two witnesses.

JAMES F. THAYER.
